C. E. BEHM

CAP

Filed Sept. 5, 1924

Fig. 6

Inventor
Charley E. Behm,
By Owen, Owen & Hampton
Attorneys

UNITED STATES PATENT OFFICE.

CHARLEY E. BEHM, OF TOLEDO, OHIO.

CAP.

Application filed September 5, 1924. Serial No. 736,011.

To all whom it may concern:

Be it known that I, CHARLEY E. BEHM, a citizen of the United States, and a resident of Toledo, in the county of Lucas and State 5 of Ohio, have invented a new and useful Cap, which invention is fully described in the following specification.

My invention has for its object to provide a self-sizing cap that will automatically 10 adjust itself to the size of the wearer's head and thus may be used by any one of a large number of wearers of caps. The invention thus provides a cap that may be sold to a class of cap wearers that is much larger 15 than caps having fixed sizes.

In certain specific embodiments of my invention slits are formed at opposite ends of the visors in the body portions of the caps and elastic means that extend across 20 the front of the cap are connected to the edges of the slits farther from the centers of the visors and means is provided for yieldingly resisting, to a certain extent, the return of the elastic means when the size 25 that fits has been produced, by the placement of the cap on the head of the wearer. Consequently the cap maintains the size 30 to which it is thus automatically set. The invention, however, may be contained in a great variety of forms of head wear and the details of the preferred embodiment of the invention may be greatly varied and still be within the purview of the claims hereinafter appended.

To illustrate a practical application of the invention I have selected a cap of the type commonly used as an outdoor cap for men, and shall describe it hereinafter. The cap selected as an example of embodiments 40 of my invention is shown in the accompanying drawings.

Figure 1 of the drawings illustrate a perspective view of a preferred form of a cap containing my invention, with the forward overhanging portion of the body of the cap released from the visor and raised to show the front exterior semi-band. Figure 2 illustrates the cap showing the overhang of the body portion secured to the visor. Figure 50 3 is a view of a fragmentary part of the cap to show one of the slits that are formed at the ends of the visor. Figure 4 shows the adjoining end portions of the external semi-band. Figure 5 shows the position of the 55 ends of the bands separated to increase the size of the cap. Figure 6 is a view of a

section of an end portion taken on the line 6-6 indicated in Fig. 4.

The invention is shown as being embodied in a type of cap commonly in vogue. 60 The body portion of the cap 1 has a forward overhanging portion 2 that is secured to the visor 3 by means of the snap button 4, in the manner well known. A decorative semi-band 5 extends across the front portion of the cap. This also is quite a common feature of the caps now usually worn.

The cap 1 is provided with slits 6 that are located at the ends of the visor, that extend into the body portion 1 of the cap. 70 The exterior decorative band 5 is divided into two parts, each of which extends from a slit to the front of the cap. Decorative straps 7 are located at the sides near the slits and so as to be slightly exposed to view 75 even though the overhanging portions 2 of the body of the cap is secured to the visor by means of the button 4. The ends of the semi-band 5 are secured to the side edges 8 of the slits 6 that are more remote from the visor, and thus these end portions of the semi-band 5 extend across the slits to the center of the front of the cap. The edges 8 extend preferably substantially at right 80 angles to the edge of the body portion of the cap, and curve away from the upper edge or corner of the semi-band 5. The other edge 9 of each slit preferably curves up into the body portion of the cap 1 along an ogee line to the end of the other edge 8. 90

The two parts 10 of the band preferably meet at the front of the cap and at the center of the visor. A flexible thick core or elongated member such as the cord 11 extends through the ends of the parts of the band and a pair of springs 12 are located on the cord and are secured to the ends of the cord at the outer ends of the springs. This may be done by producing a closer wind of the coils of the springs on the ends of the cords, as at 13, the remaining portions of the springs being freely though elastically movable over the intermediate portions of the cord. The springs 12 are also formed with ends that have closely positioned spirals 14 that form a means for easy engagement by the cloth of which the decorative band 5 is formed. The ends of the portions of the band 5 are secured to the end portions 14 of the springs. This may be done by forming 100 a small opening, the edges of which may be suitably reinforced by the hems that are 105

formed about the cord 11. These openings are so formed that the ends of the portions of the band 5 will freely move with respect to the cord 11 except as such movements are 5 yieldingly resisted by the springs 12. The cord and springs thus form an elastic flexible means for drawing the ends of the portions of the bands to the center of the cap at the front and to draw the farther edges 8 of the 10 slits over the edges 9 of the slits.

The construction is such that when the cap is placed in position on the head, the slits will be readily forced towards an open 15 position and separate to a more or less extent the inner ends of the portions of the band 5, though this movement is yieldingly resisted by the springs 12. Thus the cap will be self adjustable to any size within the permissible limitations of the slits 6. If desired, 20 this size that is thus formed by placing the cap on the head may be caused to be retained by a means that yieldingly resists the return of the springs and consequently the return of the ends of the portions of the semi-band 5. 25 Such means would comprise the straps 7 that are secured to the body portion of the cap and which may be more or less closely placed about the portions of the semi-band 5. Also the securing of the overhanging forward 30 portion 2 of the body of the cap to the visor cooperates to resist the return of the springs. These parts being made of cloth, the friction 35 between them will be exceedingly large so that if they are interengaged to a material extent the friction will prevent to a large extent relative movement of the parts. Thus when the slits are opened or their edges moved to a more or less extent by placement 40 of the cap on the head of the wearer, the cap will retain its size unless of course it is shaken so that the springs will have opportunity to cause the return of the parts to produce the smaller size. Another advantage in the use 45 of the cap is that the back of the cap may be positioned around the occipital of the head or it may be drawn down so as to be placed over or slightly above the top of the neck, and the cap will readily adjust itself to the different sizes.

50 I claim:—

1. In a cap or the like having slits extending from its edge, a band member extending across the slits and connected to the cap at its ends and having two parts having juxtaposed ends, an elongated member extending through the ends of the said parts, springs connected to the ends of the said elongated

member and the ends of the said parts and located in the said parts for pushing the adjoining ends of the parts toward each other. 60

2. In a cap or the like having slits extending from its edge, a band member extending across the slits and connected to the cap at its ends and having two parts having juxtaposed ends, an elongated member located in the said parts and elastic members connected to the elongated member and to the said parts for yieldingly maintaining the adjoining ends of the said parts in contact with each other. 70

3. In a cap having a visor, slits extending from the edge of the body of the cap and located at the ends of the visor, a two-part band extending across the slits and secured to the body of the cap at its ends, and having juxtaposed ends, a core extending through the adjoining ends of the parts of the band, springs secured to the ends of the core and located within the end positions of the said parts and connected to the ends of the said parts to press the ends toward each other. 75

4. In a cap or the like having slits extending from its edge, a band member extending across the slits and connected to the cap at its ends and having two parts having juxtaposed ends, an elongated member located in the said parts and springs connected to the elongated member and to the said parts for yieldingly maintaining the adjoining ends of the said parts in contact with each other, 85 straps surrounding the said parts of the band and connected to the cap and coacting therewith for frictionally resisting the return of the ends of the band toward each other by the springs. 90

5. In a cap having a visor, the body portion of the cap having a part extending over the visor, the cap having slits extending from its edge and located at the opposite ends of the visor, a band member extending 100 across the slits and connected to the cap at its ends and located between the visor and the said part extending over the visor, and formed of two parts having juxtaposed ends, a core member extending through the ends 105 of the said parts, springs secured to the ends of the said core and connected to the ends of the said parts for yieldingly maintaining the adjoining ends of the parts in juxtaposed relation. 110

In testimony whereof I have hereunto signed my name to this specification.

CHARLEY E. BEHM.
